Patented Oct. 17, 1967

208,964

POWER UNIT FOR AN ELECTRIC MANICURE SET OR SIMILAR ARTICLE

John G. Maxim, Mamaroneck, N.Y., assignor to Empire
Brushes, Inc., Port Chester, N.Y., a corporation of New
York

Filed Aug. 10, 1966, Ser. No. 3,404

Term of patent 14 years

(Cl. D86—10)

FIG. 1

FIG. 2

FIG. 3

FIG. 4

FIG. 5

FIG. 1 is a top plan view of a power unit for an electric manicure set or similar article showing my new design;
FIG. 2 is a front elevational view thereof;
FIG. 3 is a side elevational view thereof;
FIG. 4 is a rear elevational view thereof; and
FIG. 5 is a bottom plan view thereof.

I claim:

The ornamental design for a power unit for an electric manicure set or similar article, substantially as shown.
